UNITED STATES PATENT OFFICE.

CHARLES H. NORTON, OF WORCESTER, MASSACHUSETTS, ASSIGNOR TO NORTON COMPANY, OF WORCESTER, MASSACHUSETTS, A CORPORATION OF MASSACHUSETTS.

GRINDING-WHEEL-BALANCING DEVICE.

1,402,312.

Specification of Letters Patent. Patented Jan. 3, 1922.

Application filed April 12, 1920. Serial No. 373,342.

To all whom it may concern:

Be it known that I, CHARLES H. NORTON, a citizen of the United States of America, residing at Worcester, in the county of 5 Worcester and State of Massachusetts, have invented certain new and useful Improvements in Grinding-Wheel-Balancing Devices, of which the following is a full, clear, and exact specification.

10 My invention relates to balancing devices and more particularly to an abrasive grinding wheel having adjustable means associated therewith for balancing the wheel either initially or after the center of gravity 15 has changed. The device forming the subject of my invention constitutes a modification of the balancing device shown and described in the patent to Thure Larsson No. 1,352,005, dated September 7, 1920, and the 20 main objects of my invention are to provide a construction which is simpler in design, more easily and more cheaply manufactured, more readily assembled and more quickly adjusted than the device shown and described in the said application.

25 Further objects will be apparent from the following disclosure as set forth in the accompanying specification and the claims appended thereto.

30 In the drawings, in which like reference numerals indicate like parts:

Fig. 1 is a side elevation of a grinding wheel showing my invention applied thereto;

35 Fig. 2 is a cross section on the line 2—2 of Fig. 1;

Fig. 3 is a perspective view of the balancing member.

40 In the practice of my invention, I employ an internal peripheral surface of a grinding wheel to support a substantially U-shaped balancing member having free ends, and move such member to any desired angular position and cause these ends to engage the wheel and hold the central portion immovably against the inner surface. This U-shaped member may comprise a length of resilient material, preferably steel wire, which itself forms the balancing weight, but in my preferred form has attached thereto 45 a balancing weight of some heavy metal, such as lead.

50 Referring to the drawings, which show one specific embodiment of my invention, I have there illustrated an abrasive grinding wheel 1 having a centrally disposed aper-

ture 2 therein for fastening the wheel to a spindle and, in the form being described, annular countersunk portions or grooves 3 around the spindle aperture on each disc face 4 of the wheel. These annular grooves 60 are normally provided in order that the flanges 5, which clamp the wheel between them by means of the bolts 12 and are used to fasten the wheel to the spindle on the grinding machine, may be countersunk below the outer disc surface of the wheel. A small annular recess 6 is ordinarily left between these flanges and the outer portion of each groove 3 and I am enabled to utilize this space for the purpose of balancing the 70 wheel.

55 In its preferred form, the balancing device may comprise a substantially U-shaped length of resilient wire, the ends 7 of which are straight and the intermediate portion 8 is substantially shaped on the arc of a circle. When the device is not in place on the wheel its ends are separated by a distance greater than the diameter of the inner periphery of the countersunk groove 3 of the wheel, or as 80 illustrated this arc 8 has a greater radius than the radius of the countersunk portion of the wheel, for a purpose to be pointed out later on. This wire embodies in its construction a weight 10 made, for example, of lead 85 or other suitable material and preferably cast onto the wire. The wire is preferably formed with a sharp bend 9 at this point to hold the lead in place. The ends of the wire are formed with relatively sharp edges 11 90 which dig into the abrasive wheel when the device is applied to the wheel and serve to prevent angular displacement and frictionally and resiliently hold the device in place. As shown in the drawings, this wire is made 95 longer than half the periphery of the surface which it is to engage so that its ends will dig into the wheel beyond a diametrical line which is perpendicular to a radius drawn from the middle portion of the wire. 100 This insures an adequate frictional engagement with the wheel. To secure a perfect running balance of the wheel it will be necessary to employ two of these devices, one on each side of the wheel.

105 In order to apply the device to an unbalanced grinding wheel the intermediate portion of the wire which carries the weight is placed against the inner peripheral surface formed by the grooves 3 and the ends of the 110

wire are first flexed inwardly, that is, towards the wheel axis, and then moved into the annular recess so that when released they will bear against said surface. The portion 5 of the wire intermediate the ends and the weight are then drawn outwardly, thus causing the ends of the wire to drag back over the projecting abrasive particles, like a pawl and ratchet, and dig firmly into the material 10 of the wheel to hold the weight securely in place by the clamping action thus obtained.

In order to balance a grinding wheel and to keep it in balance after the wheel has been worn away, it is therefore merely 15 necessary to mount the wheel on a balancing stand and insert a balancing device of the kind described of the proper weight and at the proper point to balance the heavy side of the wheel.

20 By means of this construction it is therefore seen that the weight and the wire may be fastened in a firm manner to the wheel so that it will not be removed or displaced under the normal stresses of the grinding 25 operation. It will also be seen that the device in this simplified form can be used with different size wheels and can be fastened to any inner peripheral surface at any desired location thereon as may be provided 30 for this purpose.

Having thus described my invention, what I claim as new and desire to secure by Letters Patent is:

1. An abrasive wheel balancing device 35 comprising an extended resilient member which has free ends and a heavy middle portion serving as a balancing weight, said member normally having its ends separated by a distance greater than the diameter of 40 an inner peripheral surface of a wheel which it is to engage and when in use having its middle portion engaging such a surface

and its ends flexed against the resiliency of the material to frictionally engage said surface and hold the device in position. 45

2. An abrasive wheel balancing device comprising an extended member which has resilient ends and a lead balancing weight fastened to its middle portion, said member being normally curved with its ends separated by a distance greater than the diameter of an inner peripheral surface of a wheel which it is to engage and being longer than half the periphery of said surface, and when in use being bent against the resiliency 55 of the material into substantially a U-shape with the weight frictionally engaging said inner surface and its ends flexed and digging into the surface to hold the device in position. 60

3. In combination, a grinding wheel comprising an unbalanced abrasive body provided with an inner peripheral surface and a member for balancing the wheel having a weighted middle portion and resilient end portions, said member when flexed outwardly against said surface extending more than half way around the periphery and its ends digging into the surface to hold the weighted portion frictionally in engagement therewith. 70

4. In combination, a grinding wheel having a countersunk portion forming an inner peripheral surface, a wheel-holding flange of less diameter than the diameter of said 75 countersunk portion positioned therein and thus forming an annular recess and a substantially U-shaped balancing member having expandible arms located in said recess and frictionally held against said surface 80 by said arms.

Signed at Worcester, Massachusetts, this 9th day of April, 1920.

CHARLES H. NORTON.
